JAMES R. CLARK, OF ROCHESTER, NEW YORK, ASSIGNOR TO THE YAWMAN & ERBE MANUFACTURING COMPANY, OF ROCHESTER, NEW YORK, A CORPORATION OF NEW YORK

YIELDING RETAINER FOR VISIBLE INDEX CARD HOLDERS

Application filed June 26, 1930. Serial No. 463,917.

It has been proposed heretofore to retain card holders for visible index cards within trays by devices of several different kinds. In some instances spring elements have been relied upon for engagement with the holders in suchwise that the holders might be displaced against the action of the spring or springs holding them. In other instances, positive retaining devices have been employed movable to release the holders and permit their free displacement. So far as is known no practical proposal has ever been made heretofore for retaining card holders in place by yielding means which can be retracted through positive actuation to disengage the holders and permit their free displacement. The principal object of the present invention is to provide such mechanism whereby the restraint normally impressed on the holders is of the yielding nature and is yet susceptible of positive retraction by manual operation so that the holders are relieved of restraint. Still another object of the invention is to provide means for the purpose described which shall have the characteristics set forth and include, in addition, yielding means for automatically returning the restraining devices into engagement with the card holders. This last-named means may constitute the elements for exerting yielding pressure on the card holders.

In accordance with the preferred embodiment of the invention a rigid retaining bar is mounted within one channel of the tray in operative relation to the ends of the card holders. Suitable spring means are interposed between the retaining bar and the tray so as to normally urge the retaining bar yieldingly against the ends of the card holders. The retaining bar is movable longitudinally and laterally by manual force, such movement serving to withdraw it from engagement with the ends of the card holders so as to leave them free for displacement. Subsequent release of the retaining bar will permit the spring elements to return it to engagement with the ends of the card holders. By the improved construction the retaining bar is movable positively away from the card holders by proper manipulation and is also

susceptible of such movement by direct displacement of the card holders, the spring action remaining effective, at all times tending to urge its return.

The invention will be described in detail in connection with the embodiment illustrated in the drawings, in which:

Figure 1 is a view in plan of a card tray incorporating the improved retaining devices, only a few card holders being shown in place.

Figure 2 is a view similar to Figure 1 but on a larger scale, the parts being broken away in the interest of clearness and the retaining bar being shown in retracted position.

Figure 3 is a view in section through the tray shown in Figure 2 and taken on the plane indicated by the line 3—3 of Fig. 2 and looking in the direction of the arrows.

Figure 4 is a detail view of a suitable finger pull on the retaining bar taken in section at the line 4—4 of Figure 2.

Figure 5 is a detailed sectional view through the retaining bar and channel on the plane indicated by the line 5—5 of Figure 1.

The tray *a* is illustrated conventionally and may be of any approved design suited for the purpose having channels formed at its opposite side edges by reversely bent flanges *a'*, *a''*. The card holders *b* may also be of any suitable construction and normally rest within the tray under the flanges *a'*, *a''*, but are capable of removal by displacing them to the left (in the illustrated embodiment) so as to disengage their right-hand ends from the overlying flange *a''*. A stop *c* of any form, illustrated as of a solid bar, may be secured within the channel *a''*.

The present invention relates to the means for retaining the card holders *b* within the tray in the proper relation to the channels so that they will not accidentally become dislodged and yet may be removed conveniently when and as desired. A retainer bar *d* is mounted within the channel *a'* and is free to move longitudinally and laterally in a manner hereinafter to be described. As indicated at the cut-away portion of the flange *a'* in Figure 1, the retainer bar *d* in its pro-

jected position engages the left-hand ends of the card holders *b*. The bar is held yieldingly in that relationship to the card holders by means of suitable springs *e* illustrated as leaf springs disposed between the rear edge of the bar and the bottom of the channel. To prevent the accidental dislodgment of such springs they may be disposed within recesses *d'* formed at suitable intervals along the rear edge of the bar *d*. The tension of these springs may be predetermined, of course, so that their action is such as to hold the bar *d* in engagement with the ends of the card holders with sufficient firmness to prevent accidental displacement of the card holders and yet permit convenient retraction of the bar when the holders are to be removed from the tray. With the parts in the relationship indicated in Figure 1 it is evident that the bar *d* may be moved laterally by moving any one of the holders *b* to the left which might be done with the thumb nail or a suitable instrument engaged with the holder. In practice, however, it will be more convenient to use the improved devices for facilitating positive lateral displacement of the retaining bar *d* to retracted position. Further, it may be desirable to check its lateral movements in both directions by some sort of positive stops. To accomplish both of these purposes the bar *d* is provided with a plurality of openings *d²* at spaced intervals through which extend pins *f* or the equivalent, the openings being of such size and so related to the stops *f* as to permit the desired movements of the bar. The stops *f*, as shown in Figure 5, may be secured to the tray. One edge of the opening *d²* is angularly disposed to the bar so that longitudinal movement of the bar with respect to the pins *f* will cause a camming coaction between the pins and the inclined side wall of the opening, resulting in the lateral displacement of the bar. To produce the longitudinal movement of the bar the overlying flange *a'* may be slotted adjacent the front end of the tray, as indicated at *a³*, and a finger pull *g* may extend through the slot and be engaged with the bar *d*. The width of the slot *a³* is such as to permit the finger pull to partake freely of the lateral movements of the bar *d*.

The normal position of the parts is illustrated in Figure 1. Lateral displacement of the card holders at that time is resisted yieldingly by the pressure of the springs *e* on the bar *d*. If the operator desires to withdraw a card holder he will, by means of the finger piece *g*, slide the bar *d* rearwardly. This rearward movement will bring about its lateral displacement positively by engagement of the inclined side walls of the openings *d²* with the respective pins *f*. The bar will then take the position illustrated in Figure 2 at which time the springs *e* have been compressed by its lateral displacement

and the pins *f* may have reached the ends of the openings *d²*. With the bar thus retracted it is evident that any one of the card holders *b* may be slid to the left freely until its right-hand end is disengaged from the flange *a²*, at which time the card holder may be withdrawn from the tray. When the manual pressure on the finger piece *g* is removed it will be evident that the springs *e* under their increased pressure will be effective at once to return the bar *d* to its normal position in engagement with the ends of the card holders remaining in the tray. This spring action, however, will not be wholly uncontrolled because the lateral movement of the bar *d* can be no more rapid than its longitudinal movement because of the continued engagement of the pins *f* with the inclined side walls of the openings *d²*.

When, as in the illustrated embodiment, the openings *d²* are generally triangular in outline, the opening at the base of the triangle is of such width as to permit the bar *d* to be displaced laterally without any accompanying longitudinal movement, as appears clearly from Figure 1. Ordinarily, such a movement will not be desired since the operator's manipulation will be greatly facilitated by applying manual pressure to the finger piece *g* so as to bring about positive displacement of the bar *d* through the coaction of the pins *f* with the inclined side walls of the openings *d²*.

Equivalent elements may be substituted for those illustrated herein without departing from the invention and any changes within the skill of the mechanic are to be regarded within the scope of the invention so long as the conditions described are realized by means which fall within the appended claims.

What I claim is:

1. In a tray having channels along its edges and rigid members mounted transversely of the tray with the ends disposed in said channels, means to hold said members yieldingly against lateral displacement comprising a retaining bar disposed in one of said channels and engaging the ends of said members, means to press the bar against said members yieldingly, and means to retract said retaining bar positively from the ends of said members against the action of said last-named means.

2. In a tray having channels along its edges and rigid members mounted transversely of the tray with the ends disposed in said channels, means to hold said members yieldingly against lateral displacement comprising a retaining bar disposed in one of said channels and engaging the ends of said members, means to press the bar against said members yieldingly, and means to retract said retaining bar positively from the ends of said members against the action of said last-

named means, the said means to press the bar against said members being adapted to operate automatically to return the retaining bar to engagement with the ends of said members.

3. In a tray having channels along its edges and rigid members mounted transversely of the tray with the ends disposed in said channels, means to hold said members yieldingly against lateral displacement comprising a retaining bar disposed in one of said channels and engaging the ends of said members, means to press the bar against said members yieldingly, and means to retract said retaining bar positively from the ends of said members against the action of said last-named means, said retaining bar being also retractable by movement laterally of one of said members.

4. In a visible index card tray having channels along its edges, rigid card holders having their ends disposed within the channels, a retaining bar mounted in one of the channels and engaging the ends of said members, springs engaging said bar to urge it yieldingly against the ends of said members, and means adapted to operate upon longitudinal movement of said retaining bar to displace it laterally and free it from engagement with said members.

5. In a visible index card tray having channels along its edges, rigid card holders having their ends disposed within the channels, a retaining bar mounted in one of the channels and engaging the ends of said members, springs engaging said bar to urge it yieldingly against the ends of said members, and cooperating elements on the tray and bar to cause positive retraction of the bar upon longitudinal movement thereof.

6. In a visible index card tray having channels along its edges, rigid card holders having their ends disposed within the channels, a retaining bar mounted in one of the channels and engaging the ends of said members, springs engaging said bar to urge it yieldingly against the ends of said members, and cooperating elements on the tray and bar to cause positive retraction of the bar upon longitudinal movement thereof, said springs being adapted to operate automatically to return the bar to engagement with the ends of said members.

7. In a visible index card tray having channels along its edges, rigid card holders having their ends disposed within the channels, a retaining bar mounted in one of the channels and engaging the ends of said members, springs engaging said bar to urge it yieldingly against the ends of said members, and pins carried on the tray and passing through slots in the bar, said slots having inclined edges coacting with said pins whereby longitudinal movement of the bar causes its posi-

tive displacement laterally to free the ends of said members.

8. In a visible index card tray having channels along its edges, rigid card holders having their ends disposed within the channels, a retaining bar mounted in one of the channels and engaging the ends of said members, springs engaging said bar to urge it yieldingly against the ends of said members, and pins carried by the tray and passing through triangular-shaped openings in the bar, the relation of which to the pins permits lateral displacement of the bar upon lateral displacement of one of the members and causes lateral displacement of the bar upon longitudinal movement thereof.

9. In a visible index tray having channels along its opposite edges, rigid card holders having their ends engaged with the channels, a retaining bar in one of the channels engaging the ends of the members, springs operatively interposed between said bar and the bottom of said last-named channel to urge the bar yieldingly against the said members, an exposed finger piece carried with the bar whereby it may be moved longitudinally and coacting means carried by the tray and the bar to cause positive lateral displacement of the bar upon such longitudinal movement.

This specification signed this 24 day of June, A. D. 1930.
